UNITED STATES PATENT OFFICE

161,456

SHOE OR SIMILAR ARTICLE

Faie Joyce, Pasadena, Calif., assignor to Joyce, Inc., Pasadena, Calif., a corporation of California

Application September 5, 1950, Serial No. 12,056

Term of patent 3½ years

(Cl. D7—7)

To all whom it may concern:

Be it known that I, Faie Joyce, a citizen of the United States, residing in Pasadena, in the county of Los Angeles, State of California, have invented a new, original, and ornamental Design for a Shoe or Similar Article, of which the following is a specification, reference being had to the accompanying drawing, forming part thereof.

Figure 1 is a perspective view taken from the front side of a shoe showing my new design, the shoe being illustrated opened up as it would appear when on the foot of a wearer.

Figure 2 is a similar view, but showing the shoe collapsed as it appears when not being worn.

I claim:

The ornamental design for a shoe or similar article, as shown and described.

FAIE JOYCE.
